UNITED STATES PATENT OFFICE.

RUDOLF A. ISENBERG, OF SAN FRANCISCO, CALIFORNIA.

TAB FOR PLAYER ROLLS.

1,410,473.

Specification of Letters Patent. Patented Mar. 21, 1922.

Application filed February 28, 1921. Serial No. 448,674.

To all whom it may concern:

Be it known that I, RUDOLF A. ISENBERG, a citizen of the United States, residing in the city and county of San Francisco and 5 State of California, have invented a new and useful Improvement in a Tab for Player Rolls, of which the following is a specification.

My invention relates to improvements in 10 tabs for connecting the ends of player piano rolls to the receiving spool of the playing mechanism wherein an extension operates in conjunction with a securing ring to facilitate connection of the web of the player roll 15 to the receiving spool.

In the present state of the art, apertured rolls for player pianos are provided with pointed ends to the apex of which is secured a tab having a ring therein for engagement 20 with a hook upon the receiving spool of the player mechanism.

This receiver spool is located close under the tracker board and when placing the ring of the tab in connection with the hook of 25 the receiving spool said tab is so extremely short that an undue pressure and strain is applied to one of the inclined sides of the pointed end of the web or player roll so that said edge becomes easily and quickly torn 30 in such a manner that it must be secured by pasting reinforcing webs on each side thereof. The additional thickness thereby provided has a tendency to prevent proper establishment of the web upon the receiving 35 spool.

The present invention has for its object 40 the provision of a new article of manufacture comprising a tab having an extension of sufficient degree to permit threading and attachment of the web or player roll over the tracker board of a player piano and onto the hook or the receiving spool without bringing undue strain and stress upon one edge of the paper by the hand of the operator 45 during such threading process.

A further object of the invention is to provide a simple and effective means for attachment onto present webs or player rolls as well as those which may be constructed 50 hereafter.

A still further object of the invention is to provide a tab which may be easily attached to the end of a player roll and arranged to facilitate the threading and connection thereof to the receiving spool without producing undue stresses and strains 55

on the adjacent edge of the web by the hand of the operator during such threading and connecting process.

It is also an object to provide an improved 60 device of the character described wherein the tab is arranged to be enclosed within the periphery of the receiving spool to permit proper establishment of the web upon said receiving spool. 65

I accomplish these and other objects by 70 means of the improved device disclosed in the drawings forming a part of the present specification, wherein like characters of reference are used to designate similar parts throughout the said specification and drawings, and in which—

Fig. 1 is a view of the end of a web or 75 player roll attached to a receiving spool of a player piano; and

Fig. 2 is a transverse sectional view taken 80 through the approximate center of the receiving spool and disclosing a side elevation of my improved tab as applied to the end of the web or player roll.

Referring to the drawings, the numeral 1 85 is used to designate the end of a web or player roll having the usual beveled edges 2 by means of which a point is produced on the forward or front end of said roll, as disclosed in dotted and full lines in Fig. 1 of the drawings.

The dotted lines are used to indicate the 90 present arrangement wherein the fingers or hand of the operator, bear directly, and with pressure, against one of the beveled edges 2 which always results, within a comparatively short time, in a fracture or tear in said edge, as disclosed in dotted lines at 3, in Fig. 1 of the drawings. 95

The edges of this fracture or tear 3 generally turn under the web or player roll 1 which prevents an even establishment of successive layers of said web upon the receiving spool 4, which even establishment is not 100 only essential to the operation of the web 1 but is also necessary for its preservation.

This undue stress and strain is the result 105 of the close relation between the receiving spool 4 and the tracker board, not shown, resulting in a lack of space which is further aggravated by the engaging hook 6 within the annular recess 7 usually provided within the approximate longitudinal center of such spools 4. By reason of this close arrangement of the parts of the player there is insufficient room for the hand of the operator 110

ator to properly engage and manipulate the end of the web or player roll 1 and to secure the ring attached thereto without exposing the beveled edge 2 to the destroying pressure 5 from the hand of the operator as illustrated in dotted lines in Fig. 1 of the drawings.

In my improved tab for player rolls I have provided a member having two body portions 8 connected by a web 9 which is 10 bent upon itself to provide a loop for the engagement of a suitable metallic ring 11 and to bring into registration or juxtaposition the body portions 8 on each side of the point of the web or player roll 1.

15 The body portions 8 are further provided with diverging wing portions 12 which are arranged to extend along the beveled edges 2 of the web 1 a considerable distance from the point thereof so as to reinforce said beveled edges 2 and thereby reduce liability to fracture.

20 The adjacent faces of the wings 12 and body portions 8, as well as the adjacent faces of the extension 9, are gummed so that said 25 portions 8 and 12 may be readily and firmly secured to the point of the web 1, and also to more firmly connect the double layer of the extension into a single member thereby providing greater efficiency and strength to 30 said extension 9.

35 It is obvious that the tab disclosed in the present specification may easily replace a tab of the shorter type by trimming off the end of the web 1 to procure new material to which said new tab may be attached.

40 It is also obvious that with the extension 9 the process of threading and securing the end of the web 1 to the receiving roller 4 will be greatly facilitated without exposing said web to undue strain and stress which would otherwise tend to fracture the same.

45 As the receiving roller 4 is rotated it is evident that the extension 9 will be wound within the annular channel or recess 7 and thereby prevent unevenness of the roll as es-

tablished or formed upon said receiving roller 4.

Having thus described my invention, what I claim as new and desire to secure by Letters Patent is:

1. A tab for player rolls comprising a body portion having diverging wing portions, said body and wing portions being arranged to engage the point and beveled sides adjacent said point, of the end of a 50 player roll for player pianos, and likewise provided with an elongated extension formed integral therewith; and means secured to the extension for detachably connecting the same to the receiving spool of a player piano. 55

2. A tab for player rolls comprising a body portion having diverging wing portions, said body and wing portions being gummed on their adjacent faces to engage both surfaces of the point and beveled sides 60 adjacent the point of a player roll for player pianos, said body portions being connected by an extension bent upon itself to form an elongated loop; and a suitable ring mounted within the loop whereby the end 65 of said extension may be detachably connected to a receiving spool for player pianos. 70

3. A tab for player rolls comprising body portions having diverging wing portions, said body portions being connected and 75 brought into juxtaposition by a connecting portion bent upon itself to form an extension to said portions and an elongated loop, the adjacent sides of said body, wing portions and extension being gummed whereby 80 said body and wing portions may engage opposite surfaces of the end of a player roll for player pianos; and a suitable ring mounted within said loop whereby said roll may be detachably connected to a receiving 85 spool for a player piano.

In witness whereof I hereunto set my signature.

RUDOLF A. ISENBERG.
